UNITED STATES PATENT OFFICE

2,417,812

WAX BITE RIM FORMER

Paul Gordon Curren, United States Navy

Application August 20, 1945, Serial No. 611,665

3 Claims. (Cl. 18—34.1)

(Granted under the act of March 3, 1883, as
amended April 30, 1928; 370 O. G. 757)

1

This invention relates to molds for casting plastic materials and particularly to a separable mold adapted for use in forming wax bite rims in the making of artificial dentures.

Prior to this invention, it was customary to form wax bite rims from dental base plate wax in sheet form by pressing warmed sheets together and then shaping to the general curvature of the base plate. Such wax bite rims were subject to many disadvantages, such as delamination or other failure during manipulation and especially during the forming of a groove to receive the grinding mixture of artificial stone and carborundum grit.

It is an object of this invention to provide a simple and efficient mold for casting wax bite rims from molten wax.

It is a further object of this invention to provide a simple mold in two sections to facilitate the removal of the wax bite rims.

Another object of the invention is to provide means for removably securing the two sections of the mold and permitting ready separation of the sections for the removal of the formed material.

With these and other objects in view the invention consists in the combination and arrangement of parts as set forth in the claims and illustrated in the drawing, wherein

Fig. 1 is a plan view in perspective of one embodiment of my invention, showing the two sections of the mold in assembled position;

Fig. 2 is a plan view of a bite rim; and

Fig. 3 is a sectional view of the bite rim.

Referring more specifically to Fig. 1 of the drawing, an embodiment of my invention is illustrated comprising three pieces of strap material, such as strap steel having a width of about three quarters of an inch. The mold is a two-section mold, the outer section consisting of two pieces of strap metal, secured together by rivetting or the like, and the inner section consisting of one piece of strap metal with the two ends secured by rivetting or the like.

The numeral 10 indicates a U-shaped member of strap metal, forming the concave wall of the mold, and having rolled ends 11 and 12. Overlying the U-shaped member 10 is a similar member 13, rigidly secured to member 10, such as by means of rivets 14 and 15, which may be countersunk to provide a smooth mold surface. The end portions of member 13 are curved outwardly and then inwardly to form arcuate, spring-biased clips 16 and 17, the ends of which are adjacent the ends 11 and 12, respectively, of the concave wall-forming member 10. Thus, a slot is formed

2

to receive tongue-like projections of the inner mold member hereinafter described, and the spring-biased clips 16 and 17 resiliently secure these tongue-like projections.

The inner member of the mold is made up of a U-shaped, convex portion 18 and oppositely and laterally extending, clip-engaging portions 19 and 20. The convex portion 18 is complementary to concave portion 10 and spaced therefrom to form a mold recess 21 to receive the plastic material to be molded in the form of a dental bite rim. The mold recess 21 has a rectangular cross section of substantially the same dimensions at all points. Clip-engaging portions 19 and 20 are provided with depressions or grooves on each side thereof to receive the rounded ends 11 and 12 of the outer mold member 10 on one side, and the rounded ends of spring-biased clips 16 and 17 on the other side. In this manner, two tongue and groove joints are formed which hold the two sections of the mold together securely. The mold can be separated by sliding the two sections apart in the direction of the grooves, or the clips 16 and 17 may be disengaged by springing outwardly to permit the inner section of the mold to be pulled away from the molded material.

The base portion 22 serves as a spacing member and provides reenforcement for the assembled mold. As shown in the drawing, portions 18, 19, 20 and 22 are formed of a single piece of strap material, joined such as by rivet 23, the single piece being bent upon itself to form a central convex portion and oppositely extending clip engaging means.

In utilizing my novel mold for forming dental bite rims, the two sections of the mold are assembled and placed on a smooth surface, such as a glass slab. The mold surfaces and the glass slab are provided with a thin coating of any suitable separating medium, such as petrolatum or the like. The mold recess 21 is then filled with a suitable plastic material for forming the bite rim, preferably, molten dental base plate wax. After cooling until the wax is firm enough to be handled, the mold and its contents are placed in cold water to completely solidify the wax, the mold is separated, and the wax bite rim removed.

In the cooling process, the upper surface of the bite rim contracts, forming a concave depression 25, Figs. 2 and 3, which is adapted to fit over the ridge area of a base plate.

The resulting wax bite rim may be used in the conventional manner in the process of making 55 artificial dentures. For example, the bite rim

may be fitted over the ridge area of a composition base plate, waxed thereto with a hot spatula, trimmed as desired, and smoothed. A groove may then be formed in the upper surface of the bite rim to receive a grinding mixture, such as plaster of Paris and carborundum grit.

While the invention has been described with reference to the specific arrangement shown, it is not limited to the details of construction disclosed, and it is intended to cover such modifications as may come within the purposes of the improvement and the scope of the appended claims.

The invention described herein may be manufactured and used by or for the Government of the United States of America for governmental purposes without the payment of any royalties thereon or therefor.

I claim:

1. A two-section, separable, dental mold for forming wax bite rims which comprises an outer U-shaped section of strap material, a complementary inner section of strap material having a U-shaped central portion and laterally extending clip-engaging means, said two sections defining an arcuate mold recess, and a pair of clips attached to said outer section forming slots with the ends of said outer section to receive said clip-engaging means.

2. A two-section, separable, dental mold for forming bite rims from molten wax which comprises an outer U-shaped section of strap material, a complementary inner section having a

U-shaped central portion and laterally extending clip-engaging means, said two sections defining a gum-shaped recess to receive molten wax, and a pair of clips attached to said outer section, curving outwardly to provide space for the ends of said clip-engaging means, the ends of said clips being in opposed relation to the ends of said outer section, to provide slots to receive said clip-engaging means.

10 3. A two-section, separable, dental mold for forming bite rims from molten wax which comprises an outer U-shaped section of strap metal, a complementary inner section of strap metal having a U-shaped central portion and laterally and oppositely extending clip-engaging means, said two sections defining a gum-shaped recess for receiving molten wax, and a strap member attached to said outer section with ends forming arcuate, spring-biased clips contacting said clip-engaging means opposite the ends of said outer section.
